DESIGN FOR A CASING FOR A CALORIMETRIC DEVICE

Clifford Brooks Stevens, Milwaukee, Wis., assignor to Cutler-Hammer, Inc., Milwaukee, Wis., a corporation of Delaware

Application December 18, 1937, Serial No. 73,698

Term of patent 14 years

To all whom it may concern:

Be it known that I, Clifford Brooks Stevens, a citizen of the United States and a resident of Milwaukee, in the county of Milwaukee and State of Wisconsin, have invented a new, original, and ornamental Design for a Casing for a Calorimetric Device, of which the following is a specification, reference being had to the accompanying drawing, forming part thereof.

Figure 1 is a top plan view of a casing for a calorimetric device, showing my new design,

Fig. 2 is a front elevational view of said casing, Fig. 3 is a side elevational view thereof, and Fig. 4 is a perspective view on a smaller scale of the casing.

I claim:

The ornamental design for a casing for a calorimetric device, substantially as shown.

CLIFFORD BROOKS STEVENS.
